NITRAZA-ALKYLENE DERIVATIVES OF
HETEROCYCLIC AZINESMilton B. Frankel, Pasadena, Calif., assignor to Aerojet-
General Corporation, Azusa, Calif., a corporation of
Ohio
No Drawing. Filed June 13, 1957, Ser. No. 666,272
20 Claims. (Cl. 260—248)

This invention relates to new compositions of matter 10 and to their preparation. More particularly, this invention relates to heterocyclic compounds of the following general formula:

wherein X is $(NO_2)_2C=$ or

A is an alkylene radical; and R is a hydrogen, alkyl, or nitroalkyl radical.

The heterocyclic nitro compounds of this invention are useful as high explosives and can be used in any conventional explosive missile, projectile, rocket, or the like, as the main explosive charge. An example of such a missile is disclosed in United States Patent No. 2,470,162, issued May 17, 1949. One way of using the high explosives of this invention in a device such as that disclosed in United States Patent No. 2,470,162 is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time fuse-mechanism firing a detonating explosive such as lead azide or mercury fulminate.

The compounds of the present invention are also useful as pharmaceutical intermediates.

The nitropiperidines of my invention are prepared by condensing a nitraza amine with 2,2,4,4-tetranitro-1,5-pentanediol in accordance with the general reaction scheme set forth below:

wherein A and R are as defined above.

The 1,3,5-triazines of this invention are prepared by

2

condensing a nitraza amine with formaldehyde in accordance with the general reaction scheme set forth below:

wherein A and R are as defined above.

The 1,3-diazines of this invention are prepared by condensing a dinitramine with formaldehyde in accordance with the general reaction scheme set forth below:

wherein the A and R are as defined above.

To more clearly illustrate my invention, the following examples are presented. It should be understood that these examples merely serve as a means of illustrating the invention and that they are not intended to limit the scope of the invention in any way.

EXAMPLE I

Preparation of *N*-(3'-Nitraza-1'-Butyl)-3,3,5,5-Tetranitropiperidine

A mixture of 2.84 g. (0.01 mole) of 2,2,4,4-tetranitro-1,5-pentanediol, 1.56 g. (0.01 mole) of 3-nitraza-1-butyl ammonium chloride, and 50 ml. of water was warmed to 45–50° C. to effect solution and then cooled to 25° C., after which a solution of 0.82 g. (0.01 mole) of sodium acetate in 10 ml. of water was added thereto. A cream-colored solid precipitated; the solid was washed with water and dried to yield 2.5 g. (68.2%) of a product having an M.P. of 92–94° C. The washed and dried solid was recrystallized from ethylene dichloride to produce the product, *N*-(3'-nitraza-1'-butyl)-3,3,5,5-tetranitropiperidine, which had an M.P. of 96–98° C.

Analysis.—Calculated for $C_8H_{13}N_7O_{10}$: percent C, 26.16; percent H, 3.57; percent N, 26.70. Found: percent C, 26.33; percent H, 3.75; percent N, 26.71.

EXAMPLE II

Preparation of Hexahydro-1,3,5-Tris (3'-Nitraza-1'-Butyl)-1,3,5-Triazine

A mixture of 15.6 g. (0.1 mole) of 3-nitraza-1-butyl ammonium chloride, 8.1 g. (0.1 mole) of 37% formalin, and 25 ml. of water was prepared. A solution of 8.2 g. (0.1 mole) of sodium acetate in 15 ml. of water was added dropwise to the aforesaid solution. After stirring for 30 minutes, a white solid which had precipitated from the solution was collected, washed with water, and dried to yield 5.9 g. (45.0%) of a product having an M.P. of 88–90° C. The washed and dried solid was recrystallized from ethyl acetate to produce the product, hexahydro-1,3,5-tris (3'-nitraza-1'-butyl)-1,3,5-triazine, which had an M.P. of 97–97.5° C.

Analysis.—Calculated for $C_{12}H_{27}N_9O_6$: percent C, 36.63; percent H, 6.92; percent N, 32.05. Found: percent C, 36.98; percent H, 6.94; percent N, 31.68.

EXAMPLE III

Preparation of 1,3-bis (3'-Nitraza-1'-Butyl)-5,5-Dinitrohexahydro-1,3-Diazine

A mixture of 3.68 g. (0.01 mole) of 2,5,9,12-tetraaza-2,7,7,12-tetranitrotridecane, 0.81 g. (0.01 mole) of 37% formalin, and 100 ml. of water was stirred at room temperature for one hour and then stirred at a temperature of 40-50° C. for one hour. A tan-colored solid formed which was collected and dried to yield 3.2 g. (84.3%) of a mixture having an M.P. of 110-115° C. The solid was recrystallized from chloroform to produce the product 1,3-bis (3'-nitraza-1'-butyl)-5,5-dinitrohexahydro-1,3-diazine which had an M.P. of 120-121° C.

Analysis.—Calculated for $C_{10}H_{20}N_8O_8$: percent C, 31.58; percent H, 5.30; percent N, 29.46. Found: percent C, 31.72; percent H, 5.36; percent N, 28.70.

As a matter of convenience, the nitraza amines used as starting materials for the preparation of the new compounds of this invention are preferably generated in situ from their corresponding strong mineral acid salts by neutralizing the strong mineral acid salts with inorganic basic salts, such as hydroxides, carbonates, or weak organic acid salts, of alkali or alkaline earth metals. For reasons of convenience and economy, I prefer to use sodium hydroxide as my nitraza amine generating agent but other suitable agents such as, calcium hydroxide, magnesium bicarbonate, lithium carbonate, sodium acetate, etc., can be used for this purpose if desired. Any of the strong mineral acid salts such as nitric acid, hydrochloric acid, etc., salts of the nitraza amines can be utilized in the practice of my invention.

Optimum results are obtained in the nitraza amine condensation reactions when the reactions are conducted at a pH below about 8 and preferably within the range from about 4 to about 8.

Reaction temperature is not critical in the practice of this invention, the only effect of temperature variation being a corresponding increase or decrease in reaction rate.

The strong mineral acid salts of nitraza amines from which the free nitraza amines are generated in the practice of this invention are prepared by reacting a corresponding nitraza isocyanate such as, 3-nitraza-1-butyl isocyanate, with an aqueous solution of a strong mineral acid such as hydrochloric acid, as more fully disclosed in my copending U.S. patent application Serial No. 666,273, now U.S. Patent 3,000,954, filed concurrently with the present application.

The nitraza isocyanates are prepared by reacting nitraza-acid halides, such as, 4-nitrapentanoyl chloride, with alkali or alkaline earth metal azides, as for example, sodium or magnesium azide, to form the corresponding nitraza azides, and subsequently heating the nitraza azides to effect rearrangement to the desired nitraza isocyanate. Treating the 4-nitrapentanoyl chloride as described results in the formation of 3-nitraza-1-butyl isocyanate. This method of preparing nitraza isocyanates is more fully disclosed in my copending U.S. patent application Serial No. 514,384, filed June 9, 1955, now U.S. Patent 3,000,920.

The 2,2,4,4-tetranitro-1,5-pentanediol used as a starting material for the preparation of the nitropiperidines of the present invention can be prepared by reacting an alkali metal, alkaline earth metal, or ammonium salt of 2,2,4,4-tetranitro butanol with formaldehyde, as more fully disclosed in assignee's U.S. patent application Serial No. 371,150, now abandoned, filed July 29, 1953. Salts of 2,2,4,4-tetranitro butanol are prepared by acidifying the corresponding salt of dinitro ethanol, as more fully disclosed in assignee's U.S. patent application Serial No. 371,149, now abandoned, filed July 29, 1953. The 2,2,4,4-tetranitro butanol salt is prepared by the method of Duden and Poundorf, described in Ber. 38, 2033.

The dinitramines suitable as starting materials for the preparation of the nitro-substituted hydrogenated 1,3-diazines of the present invention are prepared by condensing nitraza amines (such as are employed as starting

materials for the preparation of the nitropiperidines disclosed herein) with 2,2-dinitro-1,3-propanediol, as more fully disclosed in my copending U.S. patent application Serial No. 666,275, now U.S. Patent 3,000,955, filed concurrently with the present application.

It should be pointed out that the present invention is not limited to substituted hydrogenated 1,3,5-triazines or nitro-substituted hydrogenated 1,3-diazines in which the A's and the R's represent identical radicals, respectively. It is within the scope of the invention to employ mixtures of suitable nitraza amines for the preparation of my substituted hydrogenated 1,3,5-triazines or to employ dinitramines prepared from mixtures of nitraza amines for the preparation of my nitro-substituted hydrogenated 1,3-diazines. It is thus obvious that the above two classes of compounds include members in which the radicals represented by the R's and/or the A's are not mutually equivalent. For example, the three R's in the general formula of my substituted hydrogenated 1,3,5-triazines can be identical or separate alkyl or nitroalkyl radicals; any combination of two of the three types of radicals within the scope of the invention (i.e., hydrogen, alkyl and nitroalkyl radicals); or any combination of all three types of radicals within the scope of the invention.

It will be appreciated that a wide variety of heterocyclic compounds can be prepared in accordance with the procedures taught herein. For example, the nitropiperidines: N-(4'-nitraza-1'-hexyl) - 3,3,5,5 - tetranitropiperidine and N-(3'-aza-3',5',5'-trinitro-1'-hexyl)-3,3,5,5-tetranitropiperidine are obtained when 4-nitraza-1-hexylamine and 3-aza-3,5,5-trinitro-1-hexylamine, respectively, are condensed with 2,2,4,4-tetranitro-1,5-pentanediol; the substituted hydrogenated 1,3,5-triazines: hexahydro-1,3,5-tris (4'-nitraza-1'-hexyl)-1,3,5-triazine and hexahydro-1,3,5-tris (3'-aza-3',5',5'-trinitro-1'-hexyl) - 1,3,5 - triazine are obtained when 4-nitraza-1-hexylamine and 3-aza-3,5,5-trinitro-1-hexylamine, respectively, are condensed with formaldehyde; and the nitro-substituted hydrogenated 1,3-diazines: 1,3-bis (4'-nitraza-1'-hexyl)-5,5-dinitrohexahydro-1,3-diazine and 1,3-bis (3'-aza-3',5',5'-trinitro-1'-hexyl)-5,5-dinitrohexahydro-1,3-diazine are obtained when 3,7,11,15 - tetraaza - 3,9,15 - tetranitroheptadecane and 2,2,4,9,9,14,16,16 - octanitro - 4,7,11,14 - tetraazahexadecane, respectively, are condensed with formaldehyde. Other heterocyclic compounds within the scope of my invention can be prepared simply by reacting appropriate starting materials as taught herein.

I claim:

1. As a new composition of matter, a heterocyclic compound having the general formula:

wherein X is a radical selected from the group consisting of $(\text{NO}_2)_2\text{C} =$ and

A is a lower alkylene radical; and R is a radical selected from the group consisting of hydrogen, lower alkyl, and lower nitroalkyl radicals.

2. As a new composition of matter, N-(3'-nitrazabutyl)-3,3,5,5-tetranitropiperidine having the structural formula:

3. As a new composition of matter, N-(4'-nitrazahexyl)-3,3,5,5-tetranitropiperidine having the structural formula:

4. As a new composition of matter, N-(3'-aza-3',5',5'-trinitrohexyl)-3,3,5,5-tetranitropiperidine having the structural formula:

5. As a new composition of matter, hexahydro-1,3,5-tris (3-nitrazabutyl)-1,3,5-triazine having the structural formula:

6. As a new composition of matter, hexahydro-1,3,5-tris (4-nitrazahexyl)-1,3,5-triazine having the structural formula:

7. As a new composition of matter, hexahydro-1,3,5-tris (3'-aza-3',5',5'-trinitrohexyl)-1,3,5-triazine having the structural formula:

8. As a new composition of matter, 1,3-bis (3'-nitrazabutyl)-5,5-dinitrohexahydro-1,3-diazine having the structural formula:

9. As a new composition of matter, 1,3-bis (4'-nitrazahexyl)-5,5-dinitrohexahydro-1,3-diazine having the structural formula:

10. As a new composition of matter, 1,3-bis (3'-aza-3',5',5'-trinitrohexyl)-5,5-dinitrohexahydro-1,3-diazine having the structural formula:

11. The method of preparing heterocyclic compounds having the general formula:

which comprises condensing a compound selected from the group consisting of nitraza amines having the general formula:

and dinitramines having the general formula:

with a compound selected from the group consisting of 2,2,4,4-tetranitro-1,5-pentanediol and formaldehyde; wherein X is a radical selected from the group consisting of (NO2)2C= and

40 A is a lower alkylene radical; and R is a radical selected from the group consisting of hydrogen, lower alkyl, and lower nitroalkyl radicals.

12. The method of preparing N-(3'-nitrazabutyl)-3,3,5,5-tetranitropiperidine having the structural formula:

which comprises condensing 3-nitrazabutylamine having the structural formula:

with 2,2,4,4-tetranitro-1,5-pentanediol.

13. The method of preparing N-(4'-nitrazahexyl)-3,3,5,5-tetranitropiperidine having the structural formula:

which comprises condensing 4-nitrazahexylamine having the structural formula:

14. The method of preparing N-(3'-aza-3',5',5'-trini-

trohexyl)-3,3,5,5-tetrinitropiperidine having the structural formula:

which comprises condensing 3-aza-3,5,5-trinitrohexylamine having the structural formula:

with 2,2,4,4-tetrinitro-1,5-pentanediol.

15. The method of preparing 1,3-bis (3'-nitrazabutyl)-5,5-dinitrohexahydro-1,3-diazine having the structural formula:

which comprises condensing 2,5,9,12-tetraaza-2,7,7,12-tetranitrotridecane having the structural formula:

with formaldehyde.

16. The method of preparing 1,3-bis (4'-nitrazahexyl)-5,5-dinitrohexahydro-1,3-diazine having the structural formula:

which comprises condensing 3,7,11,15-tetraaza-3,9,9,15-tetranitroheptadecane having the structural formula:

with formaldehyde.

17. The method of preparing 1,3-bis (3'-aza-3',5',5'-trinitrohexyl)-5,5-dinitrohexahydro-1,3-diazine having the structural formula:

which comprises condensing 2,2,4,9,9,14,16,16-octanitro,4,7,11,14-tetraazaheptadecane having the structural formula:

with formaldehyde.

18. The method of preparing hexahydro-1,3,5-tris (3'-nitrazabutyl) 1,3,5-triazine having the structural formula:

which comprises condensing 3-nitrazabutylamine having the structural formula:

with formaldehyde.

19. The method of preparing hexahydro-1,3,5-tris (4'-nitrazahexyl) 1,3,5-triazine having the structural formula:

35 which comprises condensing 4-nitrazahexylamine having the structural formula:

40 with formaldehyde.

20. The method of preparing hexahydro-1,3,5-tris (3'-aza-3',5',5'-trinitrohexyl)-1,3,5-triazine having the structural formula:

which comprises condensing 3-aza-3,5,5-trinitrohexylamine having the structural formula:

60 with formaldehyde.
